OF GERMANY

FACSIMILE SYSTEM

Application filed November 30, 1928, Serial No. 322,785, and in Germany December 13, 1927.

By my copending application, Serial No. 286,617, filed June 19, 1928, I have disclosed a method adapted to explore and recompose pictures as has been disclosed according to 5 which several picture lines which are explored and recorded or recomposed consecutively as to time, are not directly adjacent to each other as regards space or geometrical location.

10 In the following specification one form of this method which is readily practicable is described.

Various means suitable for carrying out the invention, as applied to different cases of 15 picture transmission, are illustrated by the accompanying drawing, wherein:

Fig. 1 illustrates the use of the invention in connection with a drum type of transmitter of known kind; while

20 Fig. 2 disclosed a receiver based upon an arrangement adapted to transfer received signs or signals upon a continuous telegraphic strip or band into facsimile in a manner such that the spots of light pass over the tape at 25 right angles to its direction of its line by line motion.

The fundamental idea of the invention is that for the photoelectric picture exploration 30 at the sending end, and for the photographic picture recording or recomposition at the receiving end, several alternating luminous spots having different locations or situations are provided. One modification of this 35 scheme inside the scope of this invention would consist in that the luminous spots may be replaced by other equivalent recording means of known type, whenever recording other than by photography is resorted to in receiving and reproducing a picture.

40 In what follows, the considerations shall, however, be confined to devices working with light at both the transmitting and receiving ends of the system in which, therefore, the motion and the change of the luminous spots 45 with relation to the incoming picture surface, by the aid of synchronizing means, are effected in the same manner as in the exploration of the outgoing picture.

Now making reference to the drawings, 50 and particularly referring to Fig. 1, 1 de-

notes the picture drum of the sending apparatus by the aid of which the invention is to be explained. Accordingly, what is to be pointed out below applies equally to the receiving end, for the distinction that at the latter spots of light controlled and varied in brightness are made to pass over the surface of the film or the recording paper, while at the transmitter end luminous spots of constant brightness come to strike the outgoing picture or the like, is immaterial in this instance. The pictured drum 1 is revolvable about spindle 3 while it is at the same time shifted axially in the direction of the arrow 5 a small distance during each rotation so as to insure exploration along a helical or spiral line. The shifting action is insured by a driving member or tappet 4 in a manner similar to that used in schemes previously well known in the art and disclosed, for example, by many previously granted United States patents, of which Nos. 888,098 and 1,699,222 may serve as examples.

The drum or cylindrical surface, according to the invention, is explored by three light spots 14, 15, 16 suitably located at equal distance from one another in constant alternation by the reflection method by the aid of the annular or similarly formed photoelectric cell 6, and the rays are so directed as to pass through the inner hole thereof. For this purpose there are employed three sources of light 8, 9, 10 or three parts of one and the same light source, say, the incandescent spiral of what is known in the art as a nitrallamp (nitrogen-filled bulb), small portions of which are allowed to pass through apertures in the diaphragm 11 and being reproduced through objective 7 upon the drum-shaped surface in the form of luminous spots 14, 15 and 16. In order to introduce a carrier frequency for the picture signals, a perforated or slit disk 12 may be mounted in well known manner in the path of the rays so as to rapidly interrupt the light rays at the desired frequency. In order to make sure that upon each revolution only one of the three light spots 14, 15, 16 will be made to operate, there is provided a uniformly rotating or intermittently moved diaphragm 13 which may be

designed in various ways, for example, as a slit disk or slit drum. A similar diaphragm, of course, must be provided at the receiving end in order to switch over the spots of light 5 at the same rhythm and at the same phase as at the sending end.

Suppose now, for example, that the picture (irrespective of what kind or type it may be) occupies the shaded portion marked 2' of the 10 drum surface. In the position, as shown, the luminous point 16 just touches the edge of the field of the picture, while the light spots 15 and 14 are still in the unused zone 2 of the drum 1. The distance between the three 15 light spots 14, 15 and 16, of course, can be varied within wide limits, according to the requirements of reception, that is, according to the periodicity of the fading phenomena. In the case here dealt with it shall be chosen 20 at a value equalling the width of 10 lines on the outgoing picture.

From the beginning of a transmission, spot 16 thus will consecutively write the first, the fourth, the seventh and the tenth line, etc., 25 while spots 14 and 15 for the time being do not participate in the transmission. Since by action of the moving diaphragm 13, spot 16 is operative only every third line, there remains first a space comprising two unexplored lines, namely, lines 2, 3, 5, 6, 8, 9, etc. If, then, owing to the axial shift of the picture drum in the direction of the arrow 5 the edge of the picture has reached the zone of spot 15, this spot begins to explore lines 2, 30 5, 8, 11, etc. After another interval of time of the same length, also spot 14 begins to take part in the transmission, this spot exploring lines 3, 6, 9, 12, etc. This can be easily accomplished by the proper adjustment 35 of the distance between the luminous spots. It will be seen that in this scheme no line will be explored twice or be recomposed or recorded twice at the receiving end, and further that never the two neighboring or 40 contiguous lines of a given line will be explored or recorded immediately before or after it, indeed, that relatively long intervals of time between these actions are inserted. The total duration of transmission of the 45 whole picture zone 2' in this arrangement is only increased by the slight amount which corresponds to the conveyance of the drum by the width of zone 2.

What has been said above respecting three 50 light exploring spots naturally holds good also for any other number of light spots, provided the number is chosen so as to be suited for the conditions. As a rule, however, two or at most three light spots will suffice.

Now referring to Fig. 2 the identical process 55 for a continuously operating facsimile telegraph recorder has been illustrated and for simplicity of illustration has been exhibited as the receiving end of the system.

The photographic film or paper strip or tape

18 corresponding to the outgoing tape is guided over the rolls 19 and is passed in the direction of the arrows 20 through the light exploring zone or the recording zone by a driving mechanism which is operated in synchronism with a similar mechanism at the sending end. Also, in this case, the light spots are designated by 14, 15, 16, and they are alternated by the diaphragm 17 which may consist, for example, of a revolving slit drum or 70 an intermittently moving diaphragm of suitable shape. The transverse movement of the light spots, that is, at right angles to the strip 18, as will be seen, is insured parallel to the axes of the guide rolls 19. The particular ways and means adopted to secure synchronism and proper phase relations between this motion at the transmitter and receiver ends is immaterial in this connection. 80

The guiding of the telegram strip is so constructed that the lower pair of rolls 19 is adapted to be shifted or adjusted by very small and accurately adjustable amounts so that, if the strip is under sufficient tension, the adjustment of the lines covered by the 90 spots 14, 15, and 16 can be insured in the sense of this invention, that is to say, the spots describe lines of different order in such a way that a line is never repeated in exploring or recording. To be sure, it is entirely possible and permissible to cause the lines to overlap more or less in order that the photographic light marks by the integration of repeated blackening may be brought out more clearly and to make them 95 thus more readily distinguishable from accidental stray marks or impressions. By the suitable selection of the length of strip between two light spots a sufficient time interval in the exploration and the recording 105 between contiguous transversal lines is provided.

Having now described my invention, what I claim is:

1. The method of picture decomposition 110 and recomposition which includes directing a plurality of light rays separated by pre-determined amounts toward a record surface, and alternately and successively changing the decomposition and recomposition of the picture from one to another of the plurality of rays.

2. The method of picture decomposition 115 and recomposition which includes directing a plurality of light rays toward a record surface, separating the individual rays by pre-determined amounts, and alternately and successively changing from one to another of the said rays for decomposing and recomposing the picture.

3. The method of picture transmission 120 which includes directing a plurality of spaced light rays toward a picture surface to be transmitted for scanning thereof, converting the varying intensities of light and shade. 125

- ow on elemental areas of the picture to be transmitted into electric currents of proportionate strength, continually and successively changing the light conversion into varying strength currents in accordance with said different rays of light, and separating the successive scanning rays by predetermined amounts so as to scan adjacent lines of the picture surface at relatively wide time intervals.
4. In a facsimile transmitting system, a plurality of light sources for directing scanning rays toward a picture surface to be transmitted, means for separating the individual scanning rays by predetermined amounts, and means for alternately and successively illuminating the picture to be transmitted by said several scanning rays for analyzing the varying intensities of light and shadow on elemental areas of the picture surface.
5. In a facsimile transmitting system having a support surface for carrying the record to be transmitted, a light source for directing scanning rays toward the record support surface, a diaphragm for separating the individual scanning rays by predetermined amounts, and a second diaphragm for successively changing the illumination of the record surface from one to another of the plurality of scanning rays.
6. In a facsimile transmitting system having a support surface for carrying the record to be transmitted, a source of light for illuminating the record, means for separating the illuminating light into a plurality of separated paths, means for alternately and successively limiting the illumination of the record surface to a single light path at any instant, and light responsive means for converting the varying intensities of light and shadow on the record surface as determined by the illumination means into proportionate strength electric currents.
7. The facsimile transmitting system claimed in claim 6 including in addition means for introducing a chopper frequency in the scanning rays for illumination of the record surface to be transmitted.
8. The system claimed in claim 6 including in addition means for controlling the separation of the plurality of light paths in such manner that the successive paths may be made to slightly overlap.
9. A facsimile transmitting system including a support surface for a picture to be transmitted, a plurality of light sources for directing scanning rays to the supported picture surface, means for separating said individual scanning rays by a predetermined amount, and means for alternately and successively changing from one to another of said scanning rays for analyzing the varying intensity of light and shade in the picture surface.
10. A facsimile system including a support surface for a facsimile to be transmitted, means for directing a plurality of spaced light rays against the supported picture surface for scanning the source, a photo cell for converting varying intensities of light and shade in the facsimile into electric current impulses, means for continually and successively influencing the photo cell from the varying intensities of light and shade in the picture surface as reflected by said light rays impinging thereon, and means for directing said light rays to said picture in such a manner that adjacent lines are scanned at relatively great time intervals.
11. A picture transmission system, including, a drum for supporting a picture to be transmitted, means for rotating said drum and continually shifting the same axially during its rotation movement, a plurality of light sources for directing scanning light rays upon the picture surface carried by said drum member, means for separating the various point where said light rays strike said picture surface, whereby the separate points are separated by a relatively great distance, photo-electric means for converting varying intensities of light and shade in the picture surface as exhibited in the reflected rays from said light source reaching said picture surface into varying strength electric current impulses, and means for continually and successively changing the influence of said photo cell from one to another of said light rays, whereby successive scanning paths of said picture take place at widely separated time intervals due to the spacing of said light rays.
